UNITED STATES PATENT OFFICE

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE

TYPEWRITING MACHINE

Continuation of application Serial No. 202,777, filed July 1, 1927. This application filed December 3, 1929.
Serial No. 411,227.

The present invention relates to cylindrical typewriter-platens, the object being to produce an inexpensive and simple construction to furnish clear-cut type-impressions with a minimum noise.

According to the invention, which has been verified by a large number of tests, sound-deadening felt-sheeting of a proper thickness tightly wound around the platen-core and covered by a tight rubber-sleeve of the usual grade, is capable of affording quietness without allowing the surface of the platen to be pitted. The degree of tension applied to the felt is a matter of extreme importance. There is used a fine grade of woolen felt which is characterized by its resiliency. The felt which is used in practice is originally substantially one-sixteenth of an inch in thickness. If wound up without tensioning, four plies of one-sixteenth of an inch felt would make a thickness of one-fourth of an inch upon the platen-core. But such a platen would not prove satisfactory. According to the present invention, when winding the felt, it is kept under very high tension, such that the four plies, which were originally one-sixteenth of an inch thick each, will form a jacket which is about one-eighth of an inch in total thickness. Tension sufficient to accomplish such a reduction in thickness, will give the desired result as to quietness and efficiency of the platen. This result is not obtained if the windings are substantially less tensioned than above described; while if the windings are placed under much greater tension than described, the completed platen will be found not to give as good results, in a typewriting machine.

Upon this body of felt, which is under permanent tension, there is placed a wearing jacket of one of the softer grades of platen-rubber, which jacket is about five thirty-seconds of an inch thick; the total diameter

of the platen being usually one and three-fourths inches.

Machines having these platens have been adopted in large numbers in telegraph offices, because they make excellent type-impressions, and are very quiet, thereby permitting the operator to listen to a message as it comes in over the telegraph wire, without being confused with the clatter of the typewriting machine upon which he is taking down such message.

This is a continuation of my application, Serial No. 202,777, filed July 1, 1927.

Other features and advantages will hereinafter appear.

In the accompanying drawings,

Figure 1 is a side elevation of the platen partly broken away.

Figure 2 is a transverse section.

Figure 3 is a sectional diagram illustrating the winding and stretching of the felt upon the platen-core.

The platen includes a cylindrical core 1, preferably of wood. Around the core is highly tensioned, in a plurality of windings, 70 felt-sheeting 2 to act as a sound-absorber, which in turn is closely fitted into the exterior wearing jacket or preferred hard-rubber shell 3.

This system of a stretched and tightly wound wrapping of felt-sheeting is glued in place at the beginning and the end of the felt-winding and produces a base for the exterior shell rigid enough to prevent indentations by the impact of the type-blows and yet of sufficient resiliency and quietness.

In particular, a form of platen is preferred having one-sixteenth inch woolen felt-sheeting, four-ply, wound around a core of bass-wood, said core to be of one and one-fourth inch outside diameter and having a one-half inch axial bore. The felt, being stretchable to a certain extent, will form a sleeve to be of one-eighth inch in total thickness, while the exterior platen-rubber-shell is made a

thickness of about five-thirty-seconds of an inch. The platen then will be of about one and three-quarters inches outside diameter. A woolen felt will hold its qualities indefinitely and does not pack under the hammering of the types.

To serve as mountings for the platen-shaft 4 end-caps 5 are secured to the core 1 by screws 6 and provided with hubs 7 to extend inwardly to fit into the hollow platen-core, while opposed hubs 8 with set screws 9 will serve to fix the platen-shaft 4, which extends through said hubs 7 and 8 and axially through the platen-core 1. The end-caps 5 shield the ends of the platen by covering up the longitudinal edges of the felt wrapping and by closing up against the hard-rubber jacket.

As above stated, the high grade woolen-felt sheeting is under permanent tension on the core, the tension being such that the thickness of the felt is thereby reduced about one-half from its original thickness, and this material, so tensioned is highly resilient, sound-absorbing, and durable.

At Figure 3 is shown diagrammatically the stretching of the felt to attenuate it as it winds on the platen-core. The leading end of the felt web is glued and tacked to the core. The four windings, each of about one thirty-second of an inch in thickness, form an approximately cylindrical shell. The outer winding is glued and tacked in place, and cut off from the unused web. After the rubber jacket 3 is tightly fitted upon the windings 2, the jacket is ground down to perfect cylindrical form and proper size.

Variations may be resorted to within the scope of the invention, and portions of the improvements may be used without others.

Having thus described my invention, I claim:

1. A platen for a typewriter including a rigid core of suitable material, a hard wrapping built up of woolen-felt-sheeting in a plurality of layers tightly wound around said core and fixed in place by gluing, and a hard wearing jacket closely fitted upon said wrapping, said sheeting under sufficient tension to substantially reduce its thickness.

2. A platen for a typewriting machine, including a core of basswood, means for securing the same upon a platen-shaft, a hard wrapping of sound-deadening material in the form of stretchable woolen-felt-sheeting wound around said core in a plurality of thicknesses and under sufficient tension to reduce its thickness materially and to form a smooth cylindrical resilient sheath, and a hard wearing jacket in the form of a tube closely fitted upon the felt wrapping.

3. A platen for a typewriting machine, including a rigid core, means for securing the same upon a platen-shaft, a hard wrapping of highly tensioned windings of sound-deadening material in the form of woolen-felt-

sheeting forming a plurality of thicknesses on said core to form a smooth cylindrical sheath of predetermined hardness and resiliency, and a thick walled wearing jacket in the form of a tube closely fitted upon the felt-wrapping.

4. A cylindrical typewriter-platen for furnishing clear-cut type-impressions and for reducing the noise of the type-blows, including a core, a multiplicity of stretched windings thereon of woolen felt sheeting whose thickness is substantially reduced by extreme tension of winding, said sheeting being sound-absorbing and being permanently under circumferential tension upon said core and hardened by said tension, means securing said windings to prevent them from slackening, and a hard wear-resisting jacket tightly enclosing said windings to form a working surface for the platen, said windings being sufficiently numerous and tight to afford quietness of the type-blows and to prevent the jacket from becoming rapidly pitted by the types.

5. A cylindrical typewriter-platen having a hard core and a jacket wound thereon, said jacket being high-grade woolen felting wound under high tension such that the felting is reduced thereby to about one-half in thickness, said felting being under permanent tension upon said core, and a wearing jacket of a soft grade of platen-rubber upon said felting.

6. A cylindrical typewriter-platen having a hard core and a jacket wound thereon, said jacket being high-grade woolen felting wound under high tension such that the felting is reduced thereby to about one-half in thickness, said felting being under permanent tension upon said core, and a wearing jacket of a soft grade of platen-rubber upon said felting, means being provided for attaching said felting to the core to maintain it permanently under such high tension.

7. A cylindrical typewriter-platen having a hard core and a jacket wound thereon, said jacket being high-grade woolen felting wound under high tension such that the felting is reduced thereby to about one-half in thickness, said felting being under permanent tension upon said core, and a wearing jacket of a soft grade of platen-rubber upon said felting, said winding forming a shell of about four plies which is one-eighth of an inch in thickness.

8. A cylindrical typewriter-platen having a hard core and a jacket wound thereon, said jacket being high-grade woolen felting wound under high tension such that the felting is reduced thereby to about one-half in thickness, said felting being under permanent tension upon said core, and a wearing jacket of a soft grade of platen-rubber upon said felting, said winding forming a shell of about four plies which is one-eighth of an inch in thick-

ness, and said rubber jacket being about five thirty-seconds of an inch in thickness.

9. A cylindrical typewriter-platen having a hard core and a jacket wound thereon, said jacket being high-grade woolen felting wound under high tension such that the felting is reduced thereby to about one-half in thickness, said felting being under permanent tension upon said core, and a wearing jacket of 10 a soft grade of platen-rubber upon said felting, said felt winding being drawn so tight as to maintain its elastic qualities indefinitely and not pack under the hammering of the types upon the platen.
